D. A. DICKINSON, OF BALTIMORE, MARYLAND.

Letters Patent No. 78,935, dated June 16, 1868.

IMPROVEMENT IN VENTILATING AND DRYING CORN AND GRAIN.

The Schedule referred to in these Letters Patent and making part of the same.

TO ALL WHOM IT MAY CONCERN:

Be it known that I, D. A. DICKINSON, of the city of Baltimore, in the State of Maryland, have invented a certain new and useful Improvement in Ventilating and Drying Corn and other Grains in Cribs, &c.; and I do hereby declare that the following is a full, clear, and exact description of the construction and operation of the same, reference being had to the accompanying drawings, and to the letters and marks thereon, which said drawings form part of this specification, and represent my invention applied to a bin.

It is very important, when any kind of grain is stored, whether it be corn in the crib or any other grain in bulk, that it be so placed as to have a free circulation of air through it, either by the natural motion of the air or by a forced circulation, of either air at the natural temperature, or heated up to whatever degree may be regarded necessary under the conditions and circumstances existing.

I have endeavored, under my invention, to make full provision for such needed circulation of air, as, also, for disturbing the corn or grain in bulk, in order to have the whole fully exposed to the air, and for the passing out and delivery of the entire quantity of corn or grain by its own weight.

In the sides or ends of the crib or bin, *a*, holes are bored, or otherwise made, for the admission of the air. Between the sides or ends, and to the inner surface of each side or end, inverted v-shaped covers, *b*, extend, which covers, in wooden structures, can be secured by screws or nails, and in brick or other structures by clamps and plates, or other suitable means and devices. These covers may be widened out to a greater extent than shown by the drawings, and the sides of these should come down to a line even with or slightly below the lower part of the holes, which is lower than the drawings show. These covers will, in many instances, serve to strengthen a crib or structure designed to hold the grain. When they may be deemed insufficient, tie-rods may be passed immediately under the angle of the cover, and secured to the sides or ends of the structure, thus making the covers also act as thrusts.

When heated air is used for ventilating or drying, one end of these covers may be higher than the other, to facilitate the circulation; and the bins or cribs may be so arranged in regard to each other that a heating-chamber or the heating-pipe may be between the ends, the heated air thus having room for free circulation through all the bins or cribs.

This invention may be applied to the bins, cribs, storehouse, or even to cars, when they are being built, or afterwards, as the holes can readily be made through the siding or walls, and the covers fitted in. When used in cars, the motion of the car will not force the grain under the covers and through the holes, as has been ascertained practically.

To the end of the bin there is attached a closed chute, *c*, having sliding doors or valves, *d* and *e*. The space between these doors may be made to answer as a measure for any certain number of bushels. The raising of the upper or inmost door will let the grain run into the space, and then the shutting of it, and the opening of the lower door, will allow the grain to run out. To this chute an indicator can be attached, so that the quantity of grain thus passed through can be registered.

When the grain comes down into the chute, that in the bin will all be more or less disturbed, bringing the portion of the grain remote from the covers nearer to them, so that whenever it is desirable to aid the ventilating or drying of the grain, a certain quantity can be taken from the bottom of the bin and put in at the top, and thus the position of the grain changed.

The bottom of the bin is inclined towards the chute, as is indicated by dotted lines through the coloring of the drawing. While the covers will allow the grain to pass down, the inclination of the bottom will permit all the grain to pass out of the bin through the chute, and thus a car-load of grain could be delivered measured.

As is evident, the covers may be made of wood or metal.

What I claim as my invention, and desire to secure by Letters Patent, is—

Ventilating and drying corn and grain by means of the inverted v-shaped covers and holes in the siding or walls, as herein recited.

This specification signed, this 21st day of May, 1868.

D. A. DICKINSON.
